UNITED STATES PATENT OFFICE

134,237

DESIGN FOR AN INSTRUCTION DEVICE OR SIMILAR ARTICLE

Thomas J. Carroll, Brighton, Mass.

Application August 5, 1942, Serial No. 107,820

Term of patent 14 years

To all whom it may concern:

Be it known that I, Thomas J. Carroll, a citizen of the United States of America, residing at Brighton, in the county of Suffolk and Commonwealth of Massachusetts, have invented a new, original, and ornamental Design for an Instruction Device or Similar Article, of which the following is a specification, reference being had to the accompanying drawings, forming a part thereof.

Fig. 1 is a plan view of an instruction device, in assembled position, showing my new design;

Fig. 2 is a similar view, on a reduced scale, showing the device in extended position; and

Fig. 3 is a section on the line 3—3 of Fig. 2.

I claim:

The ornamental design for an instruction device or similar article, substantially as shown.

THOMAS J. CARROLL.
